UNITED STATES PATENT OFFICE.

ROY H. BROWNLEE, OF PITTSBURGH, PENNSYLVANIA.

APPARATUS FOR TREATING HYDROCARBON OILS.

1,325,927.

Specification of Letters Patent. Patented Dec. 23, 1919.

Original application filed July 11, 1917, Serial No. 179,862. Divided and this application filed January 28, 1918. Serial No. 214,105.

To all whom it may concern:

Be it known that I, Roy H. BROWNLEE, a citizen of the United States, and resident of Pittsburgh, Allegheny county, Pennsylvania, have invented, a new and useful Improvement in Apparatus for Treating Hydrocarbon Oils, of which the following is a specification.

This invention is a division of that described and claimed in co-pending application Serial No. 179,862, filed July 11, 1917, and relates to an apparatus for the treatment of hydrocarbon oils, particularly to apparatus designed to effect such treatment of the oil as to cause the formation of an increased quantity of commercial gasolene from oils naturally containing the same, and cause the production of gasolene by decomposition of oil from which the naturally occurring gasolene has been removed.

One object of the invention is to provide apparatus for the treatment of hydrocarbon oils which comprises a series of directly heated inclined pipe sections, enlarged portions or drums connected in series therewith, and steam and oil connections to said system; the apparatus being so arranged that a current of steam and oil may be directed throughout the length of the system, and separation of the heavier components of the oil effected throughout the system and particularly in the drums, and liquid oil separated out and trapped in the drums may from time to time be drawn back to the initial point of introduction of the oil. A further object of the invention is to provide condensing and separating means which will economically effect a clean and readily regulated fractionation of the distillate from the cracking still into a final product of definite grades and densities, and by means of which any heavy components that may be carried over from the treating system may be returned thereto for further treatment.

In the accompanying drawings, Figure 1 is a sectional elevation of the apparatus and connections employed; Fig. 2 is a plan view of the same; and Fig. 3 is a sectional detail view of a portion of the fire heated still or initial treating apparatus, on the line 3-3, Fig. 1.

The treating apparatus proper, or still, comprises a furnace 1 in which are set the lower drums 2 and 3 and a plurality of upper drums 4; and a plurality of nests of

inclined tubes or pipe sections 5 and 6 in the interior of the furnace and connecting the drums. The pipe sections 5 and 6 are directly exposed to the heat of a plurality of oil or gas burners 7 of any suitable form, 60 while the drums 2 and 3, and the drums 4, are preferably so set in the furnace walls that they are protected from direct heating. The uppermost pipe sections 5 connect with a vapor header 8 from which a pair of upwardly inclined vapor lines 9 lead to the preheater and clarifier 10. The oil feeding system comprises a supply tank 11 connected to the preheater 10 by means of a pipe 12 arranged to introduce the oil in the form of 70 a stream or spray into the preheater, so that it passes downwardly over the baffles 10^a therein, the oil line 12 being provided with a feed pump 13. From the lower extremity of the preheater 10 the feed line 14 leads to 75 the receiving drum 2.

Steam is furnished to the treating apparatus by means of a plurality of valved connections 15 leading from the steam header 16 and provided with portions 17 extending 80 through the sludge drum 3 a considerable distance into each of the lower pipe sections 6, which pipe sections are inclined downwardly from the receiving drum 2 to the sludge drum 3. Each of the upper drums 4 85 lying directly above the receiving drum 2 may be drained thereinto by means of valved draw back connections 18, while each of the drums 4 lying directly above the sludge drum 3 may also be drained into the receiving drum 2 by means of the valved draw back connections 19. Valved draw back connections 18^a and 19^a are also provided, by means of which oil from the overlying drum or drums of each series may be drawn back 90 into the underlying treating drum or drums 4 of the same series. The sludge drum 3 is also provided with a suitable drain pipe 20 for drawing off the tarry substances produced during the treatment of the oil. 100

In conducting a treatment, dry steam is first run through the system and the pipe sections 5 and 6 raised to a suitable temperature. Oil is then introduced into the receiving drum 2, and flows downwardly 105 through the sections 6, in which it is taken up by the current of steam and carried through the overlying pipe sections and drums in an atomized and partially vaporized condition. During its progress through 110

the system the heavier components of the oil, which are in an atomized or imperfectly vaporized condition, will tend to separate out as liquid oil in the drum 4, and also in 5 the pipe sections 5, through which latter such liquid will be refluxed back counter to the current of steam and vapors into the drums. Also when the level of liquid oil in these drums rises above the orifices of the 10 lowermost pipe sections connecting therewith, this liquid oil will flow backwardly through these sections into the next lower lying drum. When so desired by the operator, the liquid in the drums 4 lying below 15 the orifices of the pipe sections therein may be run back to the receiving drum 2 by means of the valved draw backs 18 and 19 which, as shown, are so arranged that the liquid may be drawn independently from 20 each of the drums 4.

During the progress of a treatment the pipe sections 5 and 6 are maintained at a temperature which would be in excess of that requisite to vaporize substantially all 25 the components of the oil undergoing treatment if it were subjected to a simple distilling operation under merely atmospheric pressure. It will be understood that this temperature will necessarily vary according 30 to the grade of oil undergoing treatment, a lower temperature being required for the treatment of distillate than is necessary in the treatment of a crude or residual petroleum oil. The pressure throughout the system 35 is maintained at a point considerably above atmospheric, a pressure in excess of five atmospheres being preferably employed. It will be understood, moreover, that instead of dry steam some other inert gas, as for 40 instance any hydrogen-containing or a permanent hydrocarbon gas, may be employed for carrying the atomized oil and modifying the effect of the heat thereon. A combination of the two may also be employed 45 by admitting the steam through the pipes 15, and the hydrogen-containing or hydrocarbon gas through branches 15^a.

During a treatment in the still the chief 50 separation of the heavier components of the oil from the current of steam and vapors will obviously occur in the drums 4, since the increased space within the drums causes a temporary slackening in the speed of the current and affords an added opportunity 55 for the separation and deposition of the liquid oil.

The theory of operation of a treatment in the apparatus described above corresponds 60 in general to that of the processes described and claimed in my co-pending applications, Serial No. 158,165, filed Mar. 29, 1917, and Serial No. 179,862, filed July 11, 1917, of which latter application the present is a division, both processes embodying the idea 65 of separating out oil in liquid form from

a current of steam and oil vapors, and subjecting this separated liquid oil to a further similar treatment in the presence of a lesser concentration of the vapors from which it was separated than at the point of its separation. 70

The portion of the apparatus for effecting the separation and condensation of the oil discharged as vapor from the still, comprises a vapor line 21 by means of which 75 the vapors pass from the upper extremity of the preheater 10 to heat exchanging means, consisting of a pair of heat exchanging stills 22 and 23, through both of which the vapor line passes in the form of a continuous coil. Beyond the point at which the coil 21 issues from the exchanger 23, it is branched to form a vapor line 24 leading to a water cooled condensing coil 25, and a draw-off pipe 26 connecting with a vapor 80 trap 27 from which the pipe 28 leads to the supply tank 11. In the vapor line 24 is a pressure regulating valve 24^a for regulating the pressure in the vapor line 21 and pre-heater 10 and in the treating system. The 85 condenser 25 discharges into a receiving tank 29 provided with a pressure relief valve 30 and with a draw off pipe 31 having therein a vapor trap 32. From the receiving tank 29 a pipe line 33, provided with a 90 vapor trap 34 and pump 35, conducts condensate to the interior of the heat exchanging still 23 which is connected to the interior of the heat exchanging still 22 by means of the coupling 36. Connected to 95 the vapor domes 37 and 38 of the heat exchanging stills are a pair of vapor lines 39 and 40 leading to the interior of the dephlegmator 41, each of the exchanging stills also having a connection with the pipe 49 100 which connects with the pipe 28 leading to the supply tank 11. The dephlegmator 41 is provided with a steam coil 42, connected by means of the valved line 43 to the steam header 16; and with a pair of cooling coils 110 44 supplied from a water line 45. From the upper extremity of the dephlegmator a vapor line 46 leads to the final water cooled condenser 47.

In use of the apparatus, the separating 115 and condensing is as follows: The vapors from the preheater pass by means of the vapor line and coil 21 through the heat exchanging stills 22 and 23, the coil being submerged in the liquid oil in the body of the 120 exchangers. In their passage through this coil the vapors become cooled by giving up heat to the liquid oil from the receiving tank 29, and upon passing from the heat exchanging still 23, the vapors which are still uncondensed pass by way of the vapor line 24 to the condenser 25; while the products condensed during passage through the heat exchanging stills pass by way of branch pipe 26, vapor trap 27, and pipe 28, back to the 13

supply tank for re-circulation through the preheater and still. The condensate from the condenser 25 and receiving tank 29 passes into the interior of the heat exchanging stills 23 and 22 in which its lighter components are re-vaporized by the heat of the vapors in the coil 21 and pass through the vapor lines 39 and 40 to the dephlegmator 41, while the heavier components overflow continuously and pass through the pipes 49 and 28 to the supply tank 11. In order that the vapors of heavier oils than those which would be normally obtained by the heating of the coiled vapor line may be obtained when desired, a perforated steam pipe 48 is provided adjacent the bottom of each of the exchanging stills 22 and 23, these pipes being valved and connected with the steam header 16. It will be understood that the introduction of steam by means of these pipes will effect the usual purpose of bottom steam distillation, and by its lower partial pressure will lower the vapor pressure of the oil in the body of the still and permit vapors of greater density to pass over to the dephlegmator. In the dephlegmator a further and accurate regulation of the boiling point of the final product may be obtained. In this device the cooling coils 44 may serve to cool the vapors to a point at which a certain proportion of the same will condense, while the steam coil 42 may serve, in the same manner, as the steam pipes 48 in the exchangers, to prevent condensation of certain components of the vapors in the dephlegmators and permit them to pass to the final condenser 47.

The apparatus above described provides a cracking still in which certain components of the oil may be subjected to repeated treatment under conditions favorable for converting them into lighter products, particularly a commercial grade of gasolene. The separating apparatus provides means for economically and accurately grading the products of the still and in obtaining such as are of the ultimately desired density as final products of condensation. It also provides means for returning for re-treatment any product of greater density and higher boiling point than that desired for the particular purpose in view.

What I claim is:—

1. Apparatus for the treatment of hydro-carbon oils, comprising a furnace, oppositely positioned and vertically arranged series of drums in said furnace, a plurality of treating tubes inclined to the vertical connecting the drums of opposite series, means for introducing a gas into the lowermost of said treating tubes, and means for introducing oil into one of said drums.

2. Apparatus for the treatment of hydro-carbon oils, comprising a furnace, oppositely positioned and vertically arranged series of drums in said furnace, a plurality of pipe

sections inclined to the vertical connecting the drums of opposite series, means for introducing a gas into the lowermost of said pipe sections, means for introducing oil into one of said drums, and means for drawing back oil from higher lying drums into the oil receiving drum.

3. Apparatus for the treatment of hydro-carbon oils, comprising a furnace, a treating system consisting of a plurality of drums disposed in said furnace and a plurality of treating tubes inclined to the vertical connecting said drums, means for introducing oil into said system, means for introducing a gas adjacent the lower extremity thereof, and draw back lines connecting said drums with the point of introduction of the oil.

4. Apparatus for the treatment of hydro-carbon oils, comprising a furnace, oppositely positioned and vertically arranged series of drums in said furnace, a plurality of pipe sections inclined to the vertical connecting the drums of opposite series, means for introducing a gas into the lowermost of said pipe sections, means for introducing oil into one of said drums, and draw back lines interconnecting drums of the same series and connecting each with the oil receiving drum.

5. Apparatus for the treatment of hydro-carbon oils, comprising a furnace, oppositely positioned and vertically arranged series of drums in said furnace, a plurality of pipe sections inclined to the vertical connecting the drums of opposite series, means for introducing a gas into the lowermost of said pipe sections, means for introducing oil into one of said drums, means for drawing back oil from the upper drum into said oil receiving drum, a primary condenser, a vapor line from the treating system formed by said drums and pipe sections to said condenser, a heat exchanger through which said vapor line passes, connection between said heat exchanger and said primary condenser, and a final condenser having connection with said heat exchanger.

6. Apparatus for the treatment of hydro-carbon oils, comprising a furnace, oppositely positioned and vertically arranged series of drums in said furnace, a plurality of pipe sections inclined to the vertical connecting the drums of opposite series, means for introducing a gas into the lowermost of said pipe sections, means for introducing oil into one of said drums, draw back lines interconnecting drums of the same series and connecting each with the oil receiving drum, a primary condenser, a vapor line from the treating system formed by said drums and pipe sections to said condenser, a heat exchanger through which said vapor line passes, connection between said exchanger and said primary condenser, and a final condenser having connection with said heat exchanger.

heat exchanging still and said supply tank, a dephlegmator provided with steam and water coils, a final condenser, connection from the vapor space of said heat exchanging still to said dephlegmator, and a vapor line from said dephlegmator to said final condenser.

15. Apparatus for the treatment of hydrocarbon oils, comprising a supply tank, a fire heated cracking still, a primary condenser, a vapor line from said still to said primary condenser, a preheater disposed in said vapor line and having connection with said supply tank, a heat exchanging still through which said vapor line passes, connection between said primary condenser and the body of said heat exchanging still, connection between the body of said heat exchanging still and said supply tank, a dephlegmator provided with steam and water coils, a final condenser, connection from the vapor space of said heat exchanger to said dephlegmator, and a vapor line from said dephlegmator to said final condenser.

25. 16. Apparatus for the treatment of hydrocarbon oils, comprising a supply tank, a fire heated cracking still, a primary condenser, a vapor line from said still to said primary condenser, a heat exchanging still through which said vapor line passes, connection between said primary condenser and the body of said heat exchanging still, connection between the body of said heat exchanging still and said supply tank, a final condenser, a vapor line from said heat exchanger to said final condenser, and means disposed in said vapor line for regulating the density of oil passed as vapor to said final condenser.

40. 17. Apparatus for the treatment of hydrocarbon oils, comprising a supply tank, a fire heated cracking still, a primary condenser, a vapor line from said still to said primary condenser, a heat exchanging still through which said vapor line passes, connection between said primary condenser and the body of said heat exchanging still, a perforated steam coil in said heat exchanging still, connection between the body of said heat exchanging still and said supply tank, a final condenser, a vapor line from said heat exchanging still to said final condenser, and means disposed in said vapor line for regulating the density of oil passed as vapor to said final condenser.

55. 18. Apparatus for the treatment of hydrocarbon oils, comprising a supply tank, a fire heated cracking still, a primary condenser, a vapor line from said still to said

primary condenser, a preheater disposed in said vapor line and having connection with said supply tank, a heat exchanging still through which said vapor line passes, connection between said primary condenser and the body of said heat exchanging still, connection between the body of said heat exchanger and said supply tank, a final condenser, and means disposed in said vapor line for regulating the density of oil passed as vapor to said final condenser.

19. Apparatus for the treatment of hydrocarbon oils, comprising a fire heated cracking still, a primary condenser, a vapor line from said still to said primary condenser, a heat exchanging still for redistilling condensate from said primary condenser, a dephlegmator provided with steam and water coils and having connection with said heat exchanging still, a final condenser, and a vapor line from said dephlegmator to said final condenser.

20. Apparatus for the treatment of hydrocarbon oils, comprising a supply tank, a fire heated cracking still, a primary condenser, a vapor line from said still to said primary condenser, a preheater disposed in said vapor line and having connection with said supply tank, a heat exchanging still for redistilling condensate from said primary condenser, a dephlegmator provided with steam and water coils and having connection with said heat exchanging still, a final condenser, and a vapor line from said dephlegmator to said final condenser.

21. Apparatus for the treatment of hydrocarbon oils comprising a furnace, a treating system consisting of a plurality of drums in said furnace and a plurality of treating tubes inclined to the vertical connecting said drums, means for introducing oil into said system, means for introducing a gas adjacent the lower extremity thereof, draw back lines connecting said drums with the point of introduction of the oil, a primary condenser, a vapor line from said still to said condenser, a heat exchanging still through which said vapor line passes, connection from said primary condenser to said heat exchanging still, and a final condenser having connection with said heat exchanging still.

In witness whereof I have hereunto set my hand.

ROY H. BROWNLEE.
